JACK HEAD FOR FLAT KNITTING MACHINES

Arthur J. Cobert, Chattanooga, Tenn., assignor of one-half to Bryan F. F. Mills, Inc., Chattanooga, Tenn., a corporation

Application August 11, 1950, Serial No. 178,881

15 Claims. (Cl. 66—110)

1 This invention relates to jack heads for full fashioned flat knitting machines, and more particularly to an improved striking jack and jack spring. The invention also concerns the means by which the jack springs are controlled.

In the ordinary flat knitting machines, small pivoted fingers called striking jacks are mounted in a row on a carrier bar and are actuated by a slur cam to force the face of the jack against a sinker to cause the sinker to move forward in the formation of the stitch until it contacts the verge plate which is adjustable to determine the depth to which the sinkers go, and it is customary to use springs in cooperation with either the sinkers or the associated striking jacks to prevent rebound in order to preserve uniformity of the stitches.

Previously, springs have been arranged to press against an elongated heel of the striking jack, or arranged to press into a notch formed in the sinker. In both of these prior art arrangements, the pressure required of the slur cam to move the sinker forward is substantially as great as the holding pressure of the spring against rebound; however, with my novel spring and striking jack arrangement, the spring slips easily into a notch provided on the forward edge of the jack when the jack is pushed forward, but the holding power of this spring against rebound is much greater because the spring is not put under compression, as in the prior art devices, but is almost a straight wire which holds by tension. Because very little pressure is required to force my striking jack forward against the pressure of my novel spring, very little wear is had with my novel construction as compared with prior art devices where relatively great pressure was required to move the striking jacks forward against the spring pressure which was necessarily large in order to have sufficient spring pressure available to prevent rebound.

An object of my invention is to provide an improved jack head assembly for full fashioned flat knitting machines.

Another object of my invention is to provide a jack head assembly in which strong holding power is had against rebound, but relatively very little pressure is required to move the jacks forward.

Another object of my invention is to provide a jack head assembly in which the operation causes but little wear on the parts thereof.

Another object of my invention is to provide an improved striking jack.

Another object of my invention is to provide a striking jack having a notch or recess in its forward edge for cooperation with a spring for preventing rebound.

Another object of my invention is to provide an improved jack spring.

Another object of my invention is to provide

2 a jack spring constructed to be moved to operative engagement by compression and to hold against rebound by tension.

Another object of my invention is to provide a jack head having an improved jack spring bar and operating mechanism.

Other and further objects and advantages of my invention will be apparent from the following description taken in connection with the accompanying drawing in which like characters of reference designate corresponding parts throughout the several views, and wherein:

Fig. 1 is a perspective view of a striking jack made in accordance with my invention.

Fig. 2 is an end view of a jack head, showing jack spring bar assembled to it, according to my invention.

Fig. 3 is a detail view of a spring member used in connection with my striking jack.

Fig. 4 is a broken, partially disassembled view of the jack head assembly, showing the striking jack in retracted position.

Fig. 5 is a view similar to that of Fig. 4 and showing the striking jack in forward position where the same is held by the spring member. The figure further shows, in broken lines, the movement of the jack spring and jack spring bar to permit the striking jack to be returned to the retracted position.

30 In the embodiment chosen for purpose of illustration, the striking jacks 10 are rotatably supported in the usual way by their carrier bar 11 and are held in place by retainer bar 12 beneath which they roll. These jacks are provided 35 with a face 13 and rounded heel 14 of known design, and are also provided in their forward edges with the novel slot or indentation 15 for cooperation with my jack spring 16, of novel design, as will be hereinafter more fully pointed out.

The jack springs 16, one of which is provided for each striking jack 10, are firmly held in a movable jack spring bar 17 which is provided with a trunnion 18 projecting from each end thereof for vertical sliding movement in the rectangular bearings 19, one being attached to each end of the jack head by means of cap screws 20. Elongated holes 20' are provided to permit horizontal adjustment of the bearings. Reciprocating movement is imparted to the jack spring bar 17 through the trunnion 18 which is moved up and down in the rectangular bearing 19 by means of the yoke 21 on the end of rocker arm 22 which is pivoted to the jack head at 23 and to

50 which intermittent motion is transferred from the main drive of the knitting machine (not shown). Adjusting screw 21' limits the downward travel of yoke 21 and prevents the spring bar from dropping down too far, which would cause increased pressure on the springs, beyond a desirable point.

Each of the jack springs 16 is provided with a vertical section 16' which is held by the jack spring bar, then a central section extending upwardly at an angle of approximately 45° toward the striking jacks, then an intermediate section 16'' extending nearly straight up, and finally a downwardly turned tip or end section 16''' arranged for engagement with the notch 15 in the forward edge of a jack 10. On the opposite end of each jack spring is provided a heel or inturned section 16'''' to aid in securing the spring to the jack spring bar. In accordance with the usual construction, the jacks 10 move between pairs of jack walls 24, shown in Figs. 4 and 5, the end plate 24', shown in Fig. 2, having been removed; and the jack springs 16 also move between pairs of jack walls; and the springs are made substantially the same thickness as the jacks so as to prevent them from slipping in between the jack and the jack wall.

In operation, after the sinkers (not shown) and striking jacks are pulled back by the catch bar (not shown) so that the jacks are in the retracted position shown in Figs. 2 and 4, the yoke 21 moves the jack spring bar 17 downwardly, thus positioning the springs 16 for engagement, respectively, with a notch 15 in the forward edge of a jack 10. As each jack is moved forward, the tip end 16''' of a spring 16 rides gently up along the forward face of the jack until the tip slides into the slot 15, as shown in Fig. 5, when the jack reaches its forward position. In this position it will be seen that any tendency of the jack to rebound will be resisted by a pull on the spring 16, and that while the spring could easily be flexed slightly outwardly to permit the tip end to drop into the slot 15, a great deal more force would be required to flex the spring under tension to cause a lengthwise expansion, of the almost straight line wire, to release the tip 16''' from the slot 15. As the motion of the machine progresses, however, the jack spring bar 17 is raised by the yoke 21 to the position shown in broken lines in Fig. 5, and in this position the jack 10 is free to be moved back to the retracted position without having to overcome tension in the spring 16, because the raised position of the bar 17 lifts the tip 16''' off the bottom of the slot 15, as clearly shown in broken lines in Fig. 5.

It will be obvious that my invention provides a great improvement and advance in the art, and that while I have illustrated and described my invention in a very practical embodiment thereof, various changes, adaptations and modifications may be made without departing from the scope of my invention as defined in the following claims.

I claim:

1. A striking jack for a full fashioned knitting machine having a forward edge provided with a striking face, said edge being slotted for the pivotal mounting of said jack, characterized by an additional slot in said forward edge forming a shoulder for engagement with a rebound checking member.

2. In combination in a jack head for knitting machines, a pivotally mounted striking jack arranged to cause a sinker to move forward in the formation of a stitch, said jack having holding means on its forward edge for engagement with a rebound checking member, and a rebound checking member mounted for selective engagement with said holding means.

3. In combination in a jack head for knitting machines, a pivotally mounted striking jack ar-

ranged to cause a sinker to move forward in the formation of a stitch, said jack having a recess in its forward edge for reception of a rebound checking member, and a rebound checking member mounted for selective engagement in said recess.

4. In combination in a jack head for knitting machines, a pivotally mounted striking jack arranged to cause a sinker to move forward in the formation of a stitch, said jack having holding means on its forward edge for engagement with a rebound checking member, and a rebound checking member mounted for selective engagement with said holding means, said rebound checking member having a straight section, a section extending at approximately 45° to said straight section, an intermediate section in substantial alignment with said straight section, and an end section arranged for engagement with said holding means.

5. In combination in a jack head for knitting machines, a pivotally mounted striking jack arranged to cause a sinker to move forward in the formation of a stitch, said jack having a recess in its forward edge for reception of a rebound checking member, and a rebound checking member mounted for selective engagement in said recess, said rebound checking member having an upright section, a central section extending at an angle of approximately 45° to said upright section, an intermediate section extending nearly vertically, and a downwardly turned end section arranged for engagement in said recess.

6. In combination in a jack head for knitting machines, a pivotally mounted striking jack arranged to cause a sinker to move forward in the formation of a stitch, said jack having holding means on its forward edge for engagement with a rebound checking member, a carrier bar mounted for movement adjacent said striking jack, a rebound checking member carried by said bar for selective engagement with said holding means, and means for moving said bar, whereby said rebound checking member is moved out of engagement with said holding means.

7. In combination in a jack head for knitting machines, a pivotally mounted striking jack arranged to cause a sinker to move forward in the formation of a stitch, said jack having holding means on its forward edge for engagement with a rebound checking member, a bar mounted for straight line movement adjacent said striking jack, a rebound checking member carried by said bar for selective engagement with said holding means, a bearing supporting said bar, and means for moving said bar in said bearing, whereby said rebound checking member is moved out of engagement with said holding means.

8. In combination in a jack head for knitting machines, a pivotally mounted striking jack arranged to cause a sinker to move forward in the formation of a stitch, said jack having a recess in its forward edge for reception of a rebound checking member, a bar mounted for straight line movement adjacent said striking jack, a rebound checking member carried by said bar for selective engagement in said recess, a bearing supporting said bar, and a yoke carried by a pivoted member for moving said bar in said bearing, whereby said rebound checking member is moved selectively out of engagement with said recess.

9. In combination in a jack head for knitting machines, a pivotally mounted striking jack arranged to cause a sinker to move forward in the formation of a stitch, said jack having a recess

in its forward edge for reception of a rebound checking member, a bar mounted for vertical movement adjacent said striking jack, a rebound checking member carried by said bar for selective engagement in said recess, a rectangular bearing supporting said bar, and a yoke carried by a pivoted member for moving said bar up and down in said bearing, whereby said rebound checking member is moved out of engagement with said recess when said bar is moved up.

10. In combination in a jack head for knitting machines, a striking jack pivotally mounted to move forward to cause a sinker to move forward in the formation of a stitch and arranged to be withdrawn to retracted position when desired, said jack having holding means on its forward edge for engagement with a rebound checking member, a rebound checking member mounted for movement adjacent said striking jack, said rebound checking member being arranged for engagement with said holding means as said striking jack is moved forward, said rebound checking member holding said striking jack against rebound when it is in engagement with said holding means, and means to move said rebound checking member to disengage it from said striking jack, whereby said striking jack can be freely withdrawn to retracted position without resistance from said rebound checking member.

11. In combination in a jack head for knitting machines, a striking jack pivotally mounted to move forward to cause a sinker to move forward in the formation of a stitch and arranged to be withdrawn to retracted position when desired, said jack having holding means on its forward edge for engagement with a rebound checking member, a flexible rebound checking member mounted for straight line movement adjacent said striking jack, said rebound checking member being arranged to flex and ride along the forward edge of said striking jack for engagement with said holding means as said striking jack is moved forward, said rebound checking member holding said striking jack against rebound by tension in said member when it is in engagement with said holding means, and means to move said rebound checking member in a straight line to disengage said rebound checking member from said striking jack, whereby said striking jack can be freely withdrawn to retracted position without resistance from said rebound checking member.

12. In combination in a jack head for knitting machines, a striking jack pivotally mounted to move forward to cause a sinker to move forward in the formation of a stitch and arranged to be withdrawn to retracted position when desired, said jack having holding means on its forward edge for engagement with a rebound checking member, a bar mounted for straight line movement adjacent said striking jack, a flexible rebound checking member carried by said bar, said rebound checking member being arranged to flex and ride along the forward edge of said striking jack for engagement with said holding means as said striking jack is moved forward, said rebound checking member holding said striking jack against rebound by tension in said member when it is in engagement with said holding means, and means to move said bar in a straight line to disengage said rebound checking member from said striking jack, whereby said striking jack can be freely withdrawn to retracted position without resistance from said rebound checking member.

13. In combination in a jack head for knitting machines, a striking jack pivotally mounted to move forward to cause a sinker to move forward

in the formation of a stitch and arranged to be withdrawn to retracted position when desired, said jack having a recess in its forward edge for reception of a rebound checking member, a bar mounted for straight line movement adjacent said striking jack, a flexible rebound checking member carried by said bar, said rebound checking member being arranged to flex and ride along the forward edge of said striking jack for engagement in said recess as said striking jack is moved forward, said rebound checking member holding said striking jack against rebound by tension in said member when it is in engagement with said recess, and means to move said bar in a straight line to disengage said rebound checking member from said striking jack, whereby said striking jack can be freely withdrawn to retracted position without resistance from said rebound checking member.

14. In combination in a jack head for knitting machines, a striking jack pivotally mounted to move forward to cause a sinker to move forward in the formation of a stitch and arranged to be withdrawn to retracted position when desired, said jack having a recess in its forward edge for reception of a rebound checking member, a bar mounted for straight line movement adjacent said striking jack, a flexible rebound checking member carried by said bar, said rebound checking member having a free end arranged to flex and ride along the forward edge of said striking jack for engagement in said recess as said striking jack is moved forward, said rebound checking member holding said striking jack against rebound by tension in said member when it is in engagement with said recess, a bearing supporting said bar, and a yoke arranged to move said bar in a straight line to disengage said free end of said rebound checking member from said striking jack, whereby said striking jack can be freely withdrawn to retracted position without resistance from said rebound checking member.

15. In combination in a jack head for knitting machines, a striking jack pivotally mounted to move forward to cause a sinker to move forward in the formation of a stitch and arranged to be withdrawn to retracted position when desired, said jack having a recess in its forward edge for reception of a rebound checking member, a bar mounted for vertical movement adjacent said striking jack, a rebound checking member carried by said bar, said rebound checking member having a free end arranged to ride along the forward edge of said striking jack for engagement in said recess as said striking jack is moved forward, said rebound checking member holding said striking jack against rebound by tension in said member when it is in engagement with said recess, a rectangular bearing supporting said bar, and a yoke arranged to move said bar in a straight line to disengage said free end of said rebound checking member from said striking jack, whereby said striking jack can be freely withdrawn to retracted position without resistance from said rebound checking member.
